UNITED STATES PATENT OFFICE.

CHARLES R. FARGO AND PAUL O. UNGER, OF KANSAS CITY, MISSOURI, ASSIGNEES
TO IRVING-PITT MANUFACTURING COMPANY, OF KANSAS CITY, MISSOURI, A COR-
PORATION OF MISSOURI.

POSTING DEVICE.

1,396,511.

Specification of Letters Patent.

Patented Nov. 8, 1921.

Application filed March 13, 1920. Serial No. 365,507.

To all whom it may concern:

Be it known that we, CHARLES R. FARGO and PAUL O. UNGER, citizens of the United States, residing at Kansas City, in the county of Jackson and State of Missouri, have invented a certain new and useful Improvement in Posting Devices, of which the following is a specification.

Our invention relates to improvements in posting devices.

It relates particularly to a machine posting device with which leaves may be posted in a normal or in an off-set position.

The object of our invention is to provide a novel posting device comprising a holder for a loose leaf binder and loose leaves adapted to be used with an ordinary two post temporary binder, with which the leaves which are registered in the posting operation may be securely held in proper register until they are clamped between the two clamping members of the binder, and without the use of accessory holding devices, such as loose pins, straps, etc.

A further object of our invention is to provide a posting device which is simple in construction, cheap to manufacture, durable, not liable to get out of order, and which is convenient to use.

Our invention provides still further novel means for supporting the leaf registering mechanism by which the mechanism may be readily moved to and from the registering position.

Another object of our invention is to provide novel releasable means for holding the sheet registering mechanism both in and out of the registering position.

The novel features of our invention are hereinafter fully described and claimed.

In the accompanying drawings, which illustrate the preferred embodiment of our invention,

Figure 1 is a perspective view of our improved posting device, showing the arrangement of the loose leaves during a posting operation.

Fig. 2 is a side elevation, reduced, of the posting device, showing the leaf support moved from the registering to the inactive position and the leaves held clamped between the clamping members of the binder.

Fig. 3 is a perspective view of the post-

ing device, showing the binder posts partly inserted through the registered leaves.

Fig. 4 is a reduced side elevation of the posting device, showing the leaves registered, the registering mechanism in the registering position and the clamping binder member having the two posts supported by the movable leaf support, the binder posts being shown engaged with the other binder member.

Fig. 5 is a vertical sectional view of the posting device, the leaf registering mechanism being shown in solid lines in the registering position and in dotted lines in the inactive position, the binder being removed.

Fig. 6 is an end elevation of the posting device.

Fig. 7 is an edge view of one of the swinging members, which carry the support for the leaf registering mechanism.

Fig. 8 is a perspective view of the off-set registering device.

Similar reference characters designate similar parts in the different views.

1 designates one clamping member of an ordinary temporary binder having the usual posts 2 adapted to slidably and lockingly engage the other clamping member 3 of the binder.

4 designates loose leaves adapted to be releasably clamped between the members 1 and 3, each leaf adjacent to one edge having two holes 5, and intermediate of said holes having two notches 6, the holes and notches being adapted to receive the posts 2.

The members 1 and 3 have respectively hinged to them in the usual manner two covers 7 and 8.

For supporting and properly positioning the clamping member 3, so that the leaves may be laid thereon in proper register, during the posting operation, there is provided a suitable support which may consist of a frame having two longitudinal side members 9 connected by transverse bolts 10 and by a transverse guide bar consisting of an angle plate 11, the upstanding flange of which serves as a gage against which is adapted to rest one longitudinal edge of the clamping member 3, when the latter is disposed transversely on the side members 9, as shown in Figs. 1 to 4.

For properly positioning the member 3

with respect to its length, the left side member 9, looking rearwardly, has attached to it adjacent to the bar 11 an angular stop plate 12, adapted to have rest against it one end of the clamping member 3.

For supporting the loose leaves 4, during a posting operation, and prior to their being registered upon the clamping member 3 and cover 8, there is provided a longitudinally movable leaf support, which may comprise two longitudinal side members 13, which are connected by transverse rods 14.

For supporting the members 13 so that they may swing from the registering position, shown in solid lines in Fig. 5, to the inactive position shown in dotted lines in said figure, and in solid lines in Fig. 2, each member 13 has pivoted to its inner side by means of transverse pins 15 and 16, two vertical swinging members 17 and 18, Fig. 5. The members 17 are pivoted on the rear bolt 10 and the members 18 are respectively pivoted to two transverse pins 19, which extend inwardly from the side members 9 respectively.

Each swinging member 17 is provided at its lower end with a forwardly extending arm 20, provided with an inwardly extending flange 21 provided with a slot 22, through which extends a rod 23, Fig. 5, having mounted in it at opposite sides respectively of the flange 21 two pins 24 and 25 which hold the rod 23 in the flange 21 but which permits the rod to have a vertical swinging movement in the slot 22. The rod 23 extends through and is slidable in a flange 21 on a rearwardly extending arm 20 of 21 on a rearwardly extending arm 20 of the adjacent member 18, Fig. 5. Two coil springs 26 are respectively mounted on the rods 23, the forward ends bearing against the arms 20 of the adjacent members 18 and the rear ends against the arms 20 of the adjacent members 17.

When the members 13 are moved between the registering position and the inactive position, the springs 26 are first compressed and then permitted to expand, thereby resisting the swinging movement of the leaf support from either position.

For supporting the loose leaves before their registration, the upper edges of the members 13 are provided each with a notch 27 of V shape in which is located the rearwardly and downwardly inclined portion 28 of a registering plate which has the shape of an inverted V, the other portion of which designated by 29 is forwardly and downwardly inclined and is adapted to engage the edges of loose leaves which rest upon the clamping member 3. The portion 28 serves to support the lower edges of loose leaves placed on the cover 7, which may be disposed in an inclined position on the rear side of the notch 27, as shown in Fig. 1.

The end of the portion 29 which is adja-

cent to the gage plate 11 has a forwardly extending flange 30 adapted to register one set of edges of the loose leaves which are supported on the member 3, when the leaves are in the normal registered position.

For registering the leaves in an off-set position, there is provided a channel shaped guide or registering device 31, each flange of which is provided with a pair of hooks 32 adapted to enter slots 33 in the portion 29. There are a plurality of sets of slots 33, by means of which the device 31 may be adjusted laterally to different positions to suit different punchings in the leaves.

In the operation of our invention, the cover 7 is placed on the members 13, in the inclined position shown in Fig. 1. The leaves 4 are then all placed on the cover 7 with their lower edges resting on the plate 28. The clamping member 3 is then placed in position on the members 9, with its rear edge against the bar 11 and its left end against the gage plate 12. The cover 8 is placed on a plate 34 which is mounted on the upper edges of the members 9 forward of the bar 11.

The leaves are then taken one by one from the leaf support and placed on the member 3 one above the other, those leaves which are to be in the normal position being registered with one set of edges against the plate 29 and the other set of edges against the flange 30. The leaves to be off-set are disposed on the preceding registered leaves with one set of edges resting against the plate 29 and with the gage 31 located in the left hand notches 6 of the off-set leaves. The device 31 will be in the right hand notches of the normally disposed registered leaves.

After all the leaves have been registered, the holes 5 of the normally disposed leaves will register with the holes in the member 3 which receive the posts 2, and the right hand notches 6 of the off-set leaves will align with the right hand holes of the leaves which are in the normal position.

The posts 2 are then inserted through the holes 5 of the leaves which are in the normal position and into the member 3 with which the posts will engage in the usual manner. The leaves will then be securely held, the member 1 resting on the top of the plate 29, as shown in Fig. 4. The leaf support may then be swung to the position shown in dotted lines in Fig. 5 and in solid lines in Fig. 2. The clamping member 1 may then be forced downwardly to the clamping position shown in Fig. 2 at which time the leaves will be tightly clamped, and the binder may be removed and the members 13 again swung to the registering position shown in Fig. 1, after which the operation may be repeated.

We do not limit our invention to the structure shown and described, as many modifi-

cations, within the scope of the appended claims, may be made without departing from the spirit of our invention.

What we claim is:—

- 5 1. In a posting device, a holder for a loose leaf binder comprising a support for a binder member having means for positioning the latter in a leaf supporting position, a leaf support having loose leaf registering means coöperating with said positioning means, and means connecting said two supports by which said leaf support can be swung to and from the registering position.
- 10 2. In a posting device, a holder for a loose leaf binder comprising a support for a binder member having means for positioning the latter in a leaf supporting position, a leaf support having loose leaf registering means coöperating with said positioning means, two oscillatable members pivoted to the two supports and upon which the leaf support can swing to and from the registering position.
- 15 3. In a posting device, a holder for a loose leaf binder comprising a support for a binder member having means for positioning the latter in a leaf supporting position, a leaf support having loose leaf registering means coöperating with said positioning means, means connecting said two supports by which the leaf support can be swung to and from the registering position, and yielding means for holding the leaf support in the registering position.
- 20 4. In a posting device, a holder for a loose leaf binder comprising a support for a binder member having means for positioning the latter in a leaf supporting position, a leaf support having loose leaf registering means coöperating with said positioning means, means connecting said two supports by which the leaf support can be swung to and from the registering position, and means including a spring by which the leaf support may be releasably held in the registering position.
- 25 5. In a posting device, a holder for a loose leaf binder comprising a support for a binder member having means for positioning the latter in a leaf supporting position, a leaf support having loose leaf registering means coöperating with said positioning means, means by which the leaf support can be swung to and from the registering position, and yielding means for releasably holding the leaf support in or out of the registering position.
- 30 6. In a posting device, a holder for a loose leaf binder comprising a support for a binder member having means for positioning the latter in a leaf supporting position, loose leaf registering means coöperating with said means, and means by which said registering means can be swung to and from the registering position.
- 35 7. In a posting device, a holder for a loose leaf binder comprising a support for a binder member having means for positioning the latter in a leaf supporting position, loose leaf registering means coöperating with said means, means by which said registering means can be swung to and from the registering position, and yielding means for holding the registering means in the registering position.
- 40 8. In a posting device, a holder for a loose leaf binder comprising a support for a binder member having means for positioning the latter in a leaf supporting position, loose leaf registering means coöperating with said positioning means, means by which said registering means can be swung to and from the registering position, and means including a spring for releasably holding the registering means in the registering position.
- 45 9. In a posting device, a holder for a loose leaf binder comprising a support for a binder member having means for positioning the latter in a leaf supporting position, loose leaf registering means coöperating with said positioning means, and supporting members pivotally connected to said support and upon which said registering means can be swung to and from the registering position.
- 50 10. In a posting device, a holder for a loose leaf binder comprising a support for a binder member having means for positioning the latter in a leaf supporting position, loose leaf registering means coöperating with said positioning means, and a swinging support for said registering means by which the registering means can be swung to and from the registering position.
- 55 11. In a posting device, a holder for a loose leaf binder comprising a support for a binder member having means for positioning the latter in a leaf supporting position, loose leaf registering means coöperating with said positioning means, a swinging support for said registering means by which the registering means can be swung to and from the registering position, and yielding means for releasably holding the swinging support in the registering position.
- 60 12. In a posting device, a holder for a loose leaf binder comprising a support for a binder member having means for positioning the latter in a leaf supporting position, loose leaf registering means coöperating with said positioning means, a swinging support for said registering means by which the registering means can be swung to and from the registering position, and yielding means for resisting movement of said swinging support to or from the registering position.
- 65 13. In a posting device, a holder for a loose leaf binder comprising a support for

a binder member having means for positioning the latter in a leaf supporting position, loose leaf registering means cooperating with said positioning means, a support for 5 said registering means, two members pivotally supported by said binder member support and pivotally supporting the support for said registering means, and means including a spring connecting said two members arranged to resist movement thereof 10 toward or from the registering position.

14. In a posting device, a holder for a loose leaf binder comprising a support for a binder member having means for positioning the latter in a leaf supporting position, loose leaf registering means cooperating 15 with said positioning means, a support for said registering means, movable to and from the registering position, and means including a spring which yieldingly resists movement of said support for said registering means from the registering position.

15. In a posting device, a holder for a loose leaf binder comprising a support for 25 a binder member having means for positioning the latter in a leaf supporting position, loose leaf registering means cooperating with said positioning means, a support for said registering means, two members pivotally supported by said binder member support and pivotally supporting said registering means support, and a coil spring connecting said two members and arranged to resist their swinging to or from the registering position.

16. In a posting device, a holder for a loose leaf binder comprising a support for a binder member having means for positioning the latter in a leaf supporting position, 40 loose leaf registering means cooperating with said positioning means, a support for said registering means by which said registering means can swing from a registering to an inactive position, and means including a spring by which the support for the registering means is releasably held in either of said two positions.

17. In a posting device, a holder for a loose leaf binder comprising a support for a 50 binder member having means for positioning the latter in a leaf supporting position, loose leaf registering means cooperating with said positioning means, swinging members pivotally supported by said support, 55 a support for said registering means carried by said swinging members and arranged to swing from a registering position to an inactive position, and yielding means for releasably holding the support for the 60 registering means in either of said two positions.

18. In a posting device, a holder for a loose leaf binder comprising a support for a binder member having means for positioning the latter in a leaf supporting position,

loose leaf registering means cooperating with said positioning means, a support for said registering means, swinging members carried by the binder member support and carrying the registering means support, the latter being arranged to swing from a registering position to an inactive position, and yielding means connecting said swinging members arranged to releasably hold them in said two positions.

19. In a posting device, a holder for a loose leaf binder comprising a support for a binder member having means for positioning the latter in a leaf supporting position, loose leaf registering means cooperating 80 with said positioning means, a support for the registering means, a swinging member carried by the binder member support and carrying said registering means support by which the latter can swing from a registering position to an inactive position, and a spring which is compressed and then permitted to expand by said swinging member when the latter passes between said two positions.

20. In a posting device, a holder for a loose leaf binder comprising a support for a binder member having means for positioning the latter in a leaf supporting position, loose leaf registering means cooperating 95 with said positioning means, supporting means for said registering means movable from a registering to an inactive position, and means including a spring, the tension of which increases and then diminishes as the supporting means moves from one of said positions to the other for releasably holding the supporting means in said positions.

21. In a posting device, a holder for a loose leaf binder comprising a support for a binder member having means for positioning the latter in a leaf supporting position, loose leaf registering means cooperating 105 with said positioning means, swinging supporting means carrying said registering means and movable from a registering to an inactive position, and means including a spring, the tension of which increases and diminishes as the supporting means moves 110 from one of said positions to the other for releasably holding the supporting means in said position.

22. In a posting device, a holder for a loose leaf binder comprising a support for a binder member having means for positioning the latter in a leaf supporting position, loose leaf registering means cooperating 120 with said positioning means, a swinging member carried by the binder member support and carrying said registering means and upon which the registering means can swing from a registering to an inactive position, and a spring attached to said swinging member and arranged to have its tension 125 130

increased and then diminished as the swinging member passes from one of said positions to the other.

23. In a posting device, a holder for a loose leaf binder comprising a support for a binder member having means for positioning the latter in a leaf supporting position, loose leaf registering means coöperating with said positioning means, a support for the registering means, two swinging members carried by the binder member support and carrying said registering means support, and a spring connecting said two swinging members and arranged to have its tension increased and then diminished as the swinging members swing from a registering to an inactive position.

24. In a posting device, a support for the binder member having positioning means therefor, loose leaf registering means coöperating with said positioning means, a support for the registering means, two swinging members carried by the binder member support and carrying said registering means support by which the latter can swing from a registering to an inactive position, a rod carried by one of said swinging members, and a coil spring encircling said rod and having a bearing against one of said swinging members and arranged to have its tension increased and then diminished as the swinging members pass from one of said positions to the other.

25. In a posting device, a support for the binder member having positioning means therefor, loose leaf registering means coöperating with said positioning means, a support for the registering means, two swinging members carried by the binder member support and carrying said registering means support so that the latter can swing from the registering to an inactive position, a rod carried by one of said swinging members and slidably engaging the other swinging member, and a coil spring encircling said rod and having its ends bearing respectively against said swinging members and arranged to resist the swinging of said swinging members from one of said positions to the other position.

26. In a posting apparatus, a support for a binder member, and means for registering loose leaves supported by the binder member, the registering means being movable from the registering position on said support.

27. In a posting apparatus, a support for a binder member, and means for registering loose leaves supported by the binder member and provided with a rib adapted to enter notches in the registered edges of said leaves, the registering means being movable on said support to and from the registering position.

28. In a posting apparatus, a support for

a binder member, and a loose leaf support having registering means adapted to engage the edges of loose leaves carried by the binder member, the leaf support being movable to and from the registering position. 70

29. In a posting apparatus, a support for a binder member, and a loose leaf support having registering means adapted to engage the edges of loose leaves carried by the binder member and provided with a registering device adapted to enter notches in said edges, the leaf support being movable to and from the registering position. 75

30. In a posting apparatus, a loose leaf registering member adapted to engage edges 80 of loose leaves having notches in said edges and having a slot, and a registering device adapted to enter said notches and having a hook adapted to enter said slot and lock said device to said member. 85

31. In a posting apparatus, a support for a binder member, a loose leaf support having registering means adapted to engage the edges of loose leaves carried by the binder member, the leaf support being movable to 90 and from the registering position, and releasable means for holding the leaf support in the registering position.

32. In a posting apparatus, a support for a binder member, a loose leaf support having 95 loose leaf registering means adapted to engage edges of leaves carried by the binder member and having means for registering said leaves in a normal and in an offset position, and releasable means for holding the 100 leaf support in the registering position.

33. In a posting apparatus, a support for a clamping member of a binder having means for properly positioning said member, and registering means coöperating with 105 said support and having means for engaging two adjacent edges of each of a plurality of loose leaves carried on said member, the registering means being movable to and from the registering position. 110

34. In a posting apparatus, a support for a clamping member of a binder having means for properly positioning said member, a leaf support, and registering means carried by said leaf support and having 115 means for engaging two adjacent edges of each of a plurality of loose leaves carried on said member, said leaf support being movable to and from a position in which the registering means will be in operative position. 120

35. In a posting apparatus, a support for a clamping member of a binder having means for properly positioning said member, a leaf support, registering means carried by 125 said leaf support and adapted to engage two adjacent edges of each of a plurality of loose leaves carried on said member, the registering means being movable to and from the registering position with said leaf 130

support, and a registering device on said registering means adapted to enter notches in one set of edges of said leaves.

36. In a posting apparatus, a support for 5 a clamping member of a binder having means for properly positioning said member, a plate arranged to engage and register one set of edges of loose leaves carried by said member and having a flange arranged 10 to engage and register an adjacent edge of each of said leaves, and supporting means for said plate movable therewith to and from the registering position.

37. In a posting apparatus, a support for 15 a clamping member of a binder having means for properly positioning said mem-

ber, a plate arranged to engage one set of edges of loose leaves carried by said member and having a flange arranged to engage an adjacent set of edges of said leaves, a registering member carried by said plate and adapted to enter notches in the adjacent edges of said leaves, whereby the leaves may be registered in the normal and in an offset position, and supporting means for said plate movable therewith to and from the registering position. 20 25

In testimony whereof we have signed our names to this specification.

CHARLES R. FARGO.
PAUL O. UNGER.
